UNITED STATES PATENT OFFICE

95,192

DESIGN FOR A TICKET HOLDER OR ARTICLE OF SIMILAR NATURE

Ralph A. Vogel, Columbus, Ohio

Application January 28, 1935, Serial No. 55,111

Term of patent 14 years

To all whom it may concern:

Be it known that I, Ralph A. Vogel, a citizen of the United States of America, residing at Columbus, in the county of Franklin and State of Ohio, have invented a new, original and ornamental Design for a Ticket Holder or Article of Similar Nature, of which the following is the specification, reference being had to the accompanying drawing, forming a part hereof:

I claim:

The ornamental design for a ticket holder or article of similar nature, as shown.

RALPH A. VOGEL.
